UNITED STATES PATENT OFFICE

2,605,848

DRY CHEMICAL FIRE EXTINGUISHER

Philip M. Carter, Yonkers, N. Y., assignor to
Carnoy Products Corporation, Elmsford, N. Y.,
a corporation of New York.

Application April 28, 1950, Serial No. 158,743

8 Claims. (Cl. 169—31)

1

The present invention relates to a novel and improved dry chemical fire extinguisher in which the dry chemical is maintained under pressure and is to be projected by propellant gas onto the fire when the extinguisher is used.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation of a typical, illustrative and preferred embodiment of the preferred invention;

Figure 2 is a top plan view of the embodiment shown in Figure 1;

Figure 3 is a fragmentary enlarged front elevation of the embodiment shown in Figures 1 and 2;

Figures 4 and 5 are perspective details of certain of the parts shown in the other figures;

Figure 6 is a vertical section taken on the line 6—6 of Figure 3;

Figure 7 is a sectional view taken on the line 1—1 of Figure 6; and

Figure 8 is a perspective showing the operating handle used in the present embodiment.

The present invention has for its object the provision of a novel and improved fire extinguisher of the type in which a dry extinguishing powder is to be propelled by means of a suitable gas under pressure. A further object of the invention is the provision of such an extinguisher which is more compact, more easily and quickly recharged and which may be more rapidly put into operation than those heretofore developed. Still another object of the invention is the provision of a lightweight, high capacity fire extinguisher which is extremely efficient in operation and which is instantly available for use in case of fire, and at all times gives a visual indication of whether or not it is ready for service.

In accordance with the present invention, there is provided a dry chemical fire extinguisher having a single pressure container which is charged

2

with a dry extinguishing powder and a propellant gas under relatively high pressure, the container having an opening at one end through which it may be filled with powder and which may be closed by means of a valve and nozzle assembly, the valve controlling the flow of gas and powder from the container to the nozzle and normally held in closed position, ready to be opened when the extinguisher is to be put into service. Associated with the valve nozzle assembly pressure gauge communicating with the interior of the container showing whether or not the container is fully charged with gas, and a relief aperture normally filled with a suitable alloy is provided so as to release the contents of the container in the event that it becomes heated to an excessive temperature such as might otherwise cause the building up of a dangerous pressure within the container. The valve means comprise a plunger valve which is normally held in seated position by means of a relatively strong spring, and is lifted from its seat by means of a hand lever so that powder and propellant gas are supplied from the container to the nozzle. In order to increase the effectiveness of the seating of the valve, and to prevent against accidental opening of the valve, means are provided for exerting additional pressure on the valve plunger so as to maintain it seated and to render the handle or valve opening means normally ineffective, the additional valve seating means being quickly releasable, adjustable and normally sealed so that the operating handle can only be operated after the seal has been broken, thereby immediately indicating that the extinguisher may have been used and should be inspected or recharged. The handle locking and sealing means is preferably in the form of a toggle member mounted on a threaded post which cooperates with a pivoted bail overlying the plunger and exerting additional pressure on the plunger, the bail being bifurcated and normally holding the threaded post against turning, and at the same time securing a nut or other threaded member on the end of the plunger.

It will be understood that the foregoing general description and the following detailed description as well are exemplary and explanatory of the invention but are not restrictive thereof.

Referring now in detail to the illustrative and preferred embodiment of the invention as shown in the accompanying drawings, there is provided a gas and dry powder cylindrical container 10, often referred to as a "bottle." The bottle is conveniently made as a steel spinning and at

its upper end is provided with a threaded aperture 11 through which the bottle may be charged with the required quantity of dry extinguishing powder, and thereafter closed by means of the threaded portion 12 of the valved nozzle assembly 14. The valved nozzle assembly is provided with a central cylindrical bore extending axially of the threaded portion 12, and connected to a tube 16 which extends downwardly to near the bottom of the bottle 10 so as to pick up the dry powder as it is expelled from the bottle through the tube 16 and delivered to the discharge nozzle 18. The valved nozzle assembly is sealed to the bottle 10 by means of a suitable sealing ring 20 which prevents escape of gas or powder except through the tube 16 and nozzle 18, and at the same time the sealing ring 20 allows the valved nozzle assembly 14 to be removed from the bottle and replaced thereon after the bottle has been recharged with powder.

In order to prevent injury through accidental opening of the bottle by unscrewing the valved nozzle 14 while the bottle is still under heavy gas pressure, a bleed hole 22 extends from the cylindrical bore 24 to the exterior of the threaded portion 12 so that as the valved nozzle assembly 14 is unscrewed from the bottle, any gas pressure remaining in the bottle 10 will be discharged to the atmosphere after one or two turns and long before the bottle has been unscrewed from the assembly.

A cylindrical bore 24 at its intermediate portion is of reduced diameter and is provided with an upper face 26 forming a valve seat against which presses a valve closing disc 28, formed of some impervious, slightly resilient material, such as nylon, which is received within a recess in the enlarged end 30 of a plunger 32, the enlarged end 30 substantially filling the enlarged portion 34 of the cylindrical bore, and preventing excessive leakage of gas when the valve is unseated. Plunger 32 is normally pressed downwardly with the valve disc 28 against its seat 26 by means of a relatively heavy helical compression spring 36 received within the recessed end of a retainer 38 which is threaded into the upper end of the cylindrical bore leaving the upper end of the plunger exposed.

Communicating between the cylindrical bore 24 and the nozzle 18 is a passageway 40 delivering to the nozzle 18 the dry powder suspended in the expanding propellant gas issuing from the valve. The nozzle 18 comprises a cylindrical member threaded on the exterior of a hollow lateral projection 42, and extending therefrom, being provided with a plurality of apertures 44 which supply the powder and expanding gas to the interior cylindrical end 46 of the nozzle, the gas powder being distributed by means of a conical member 48 supported on a threaded stud 50 in the wall portion 52 of the nozzle so that the propelled powder forms a somewhat conical and more or less hollow stream of powder which may be directed at the base of the fire and even as far away as twenty or thirty feet.

Means are provided for opening the valve and these means comprise a hand lever 60 having an apertured end 62 and a fulcrum portion 64, the slot 62 being adapted to be passed over the end of the plunger 32 and to be retained thereon by means of nut 66, while the fulcrum 64 rests on the upper surface of the flange 38 and provides a pivot for the handle 60. A cooperating hand grip member 68 is pivotally mounted to the assembly 14 by means of a pivot pin 70 and pro-

vides a convenient member to be gripped by the fingers as the hand lever 60 is rocked about its pivot 64 as the valve is moved to open position.

Means are also provided for exerting additional pressure on the valve plunger 32 so as to hold it securely closed, and to prevent accidental opening of the valve, these means serving to exert pressure on the valve plunger 32 in addition to the pressure exerted by the compression spring 36. As embodied, a bail 74 is pivotally mounted between lugs 76 extending upwardly from the assembly 14, the underside of the bail being channeled, as clearly shown in Figure 4 so that its side members 78 may engage with the sides of the nut 66 and hold it against rotation relatively to the plunger 32. The forward end of the bail 74 is bifurcated, as at 80, providing a slot which fits over a threaded post 82 having flat sides, the post being threaded into and extending upwardly from the assembly 14, the bail thereby serving to prevent rotation of the post 82 and to hold the post in its desired position of adjustment.

Means are also provided for locking the bail in its valve closing position, while providing for rapid release of this locking condition. For this purpose a toggle lever 84 is pivotally mounted at 86 on the upper end of the post 82, the toggle lever being formed with a finger engaging portion 88 by which the lever may be instantly moved to unlocked position. The lower end of the lever 84 is preferably provided with a face 90 which bears against the upper surface of the bail 74 and exerts the desired amount of pressure thereon, this pressure being controlled by the threaded portion of the post 82.

In order to seal the toggle lever 84 against accidental unlocking which might result in accidental opening of the valve and partial discharge of the contents, the toggle lever 84 and the threaded post 82 are provided with holes 92 which register with the toggle lever in valve locking position and they may be sealed by means of a wire seal 94. Lifting up on the finger lever 88 to move the toggle lever 84 to unlocked position shears the sealing wire thereby rendering the extinguisher instantly ready for emergency use and at the same time providing a definite warning indication that the extinguisher may have been partially or fully discharged and should be reinspected or recharged.

The apertured end of the lever 60 is preferably positioned between a metal washer 96 and a resilient washer 98, the resilient washer 98 allowing the handle and plunger 32 to be moved downwardly by the sealing pressure exerted by the toggle lever 84, while the handle 60 is held in position by the nut 66 which may also serve to adjust the pressure exerted on the rod 32 by the toggle sealing lever 84.

The external and downwardly depending sides of the toggle lever 84 are preferably closely fitted to the flat sides of the threaded posts 82, thereby improving the shearing action on the wire seal 94, and permitting the toggle lever 84 to serve as a handy wrench for adjustment of the position of the threaded post 82. For this purpose the pivot pin 86 is formed as a removable and threaded pin, and when removed the toggle lever 84 may be used to turn the post 82 if the bail 74 has been moved free of the post 82. Pin 86 is secured to the nozzle member 18 by means of a flexible chain 100 so that if either of them remains on the assembly 14 the

other is secured against accidental loss or misplacement.

In order to provide a constant, reliable, visual indication of the condition of the extinguisher, a pressure gauge 102 is mounted on the assembly 14 and directly communicates with the interior of the bottle 10 through the fine passageway 104. Pressure gauge 102 preferably is a scale divided into three parts 106, 107 and 108. The scale portion 108 indicates an excessive pressure, the portion 107 a normal operating pressure, and the portion 106 a dangerously low pressure which might render the extinguisher ineffective.

In order to guard against the possibility of explosion in case an extinguisher was allowed to remain in a burning building, or otherwise exposed to excessive heat which might cause a dangerous increase in the pressure within the bottle, a plug 110 having a fusible plug 112 is threaded into the assembly 14 and communicates directly with the interior of the bottle 10 by means of a fine passageway 114. The fusible plug 112 may be made of suitable alloy to allow it to melt at any desired temperature, for instance about 165° F., thereby opening the bore in the plug 110 and allowing the gas pressure within the bottle fully to escape to the atmosphere before the bottle has been heated sufficiently to create a dangerous internal pressure.

The bottle is normally charged about three-fourths full with a dry, free-flowing extinguishing powder such as a special grade of sodium bicarbonate mixed with other ingredients, and the gas is usually nitrogen or carbon dioxide at approximately 350 pounds pressure per square inch. Under these conditions, and assuming that the bottle became heated to approximately 170° F. before the fusible plug 112 released, the pressure within the bottle would be approximately 410 pounds, or well within the safety limits of the bottle.

In the operation of the bottle the hand engaged levers 60 and 68 are grasped and pressed together after the toggle lever 84 has been moved to unlocked position cutting the seal wire 94. As the handle 60 is depressed the valve plunger 32 is raised and a powerful stream of gas-propelled dry powder issues from the nozzle 18 and may be directed at the fire so long as the handle 60 is depressed.

The invention in its broader aspects is not limited to the specific mechanism shown and described but departures may be made therefrom within the scope of the accompanying claims without departing from the principles of the invention and without sacrificing its chief advantages.

What is claimed is:

1. In a dry chemical fire extinguisher having a pressure bottle to be charged with dry powder and a propellant gas under pressure and having a threaded aperture in one end thereof, the combination of a valved nozzle assembly having a threaded portion to close said aperture and con-

trol the flow of gas and powder from the bottle to the nozzle and comprising a body portion having a valve seat formed therein, a plunger carrying a valve closing disc, a spring urging the plunger to valve closing position, means for moving the plunger to valve opening position, a bail overlying the outer end of the plunger and engageable therewith for increasing the pressure with which the valve plunger is seated and means for releasably locking the bail in plunger seating position said locking means including a post threaded in said body portion and variably positionable to vary the pressure with which the bail engages the plunger.

15 2. A dry chemical fire extinguisher as claimed in claim 1 in which the bail is pivoted and one end is bifurcated to fit over the threaded post, and a toggle lever is pivotally mounted on the post to releasably engage the bail and press it against the plunger, said post and lever forming the bail locking means.

20 3. A dry chemical fire extinguisher as claimed in claim 2 in which the plunger lifting means comprises a lever pivoted on the body portion and engaging the plunger between the bail and body portion.

25 4. A dry chemical fire extinguisher as claimed in claim 1 in which the plunger lifting means comprises a lever pivoted on the body portion and engaging the plunger between the bail and body portion.

30 5. A dry chemical fire extinguisher as claimed in claim 1 in which the plunger is mounted for axial movement in a straight bore and a passage 35 communicates between the valve seat and the nozzle.

30 6. A dry chemical fire extinguisher as claimed in claim 1 in which a pressure gauge is mounted on the valved nozzle assembly and communicates directly with the interior of the bottle.

40 7. A dry chemical fire extinguisher as claimed in claim 1 in which the bail is pivoted and channelled to fit over and secure a nut threaded on the end of the plunger, the bail is bifurcated to fit over and prevent rotation of a threaded post having flat sides, and a toggle lever is pivotally mounted on the post to releasably engage the bail and press it against the plunger, said post and lever forming a bail locking means.

50 8. A dry chemical fire extinguisher as claimed in claim 7 in which the lever and post are apertured to receive a sealing wire.
